[57] **ABSTRACT**

A connection between a corner fence post having two

longitudinal sides arranged at right angles to one another, a short side connected to the free end of each longitudinal side at right angles thereto, and an inwardly extending flange attached to each side at right angles thereto, and an inwardly extending flange attached to each side at right angles thereto with a vertical opening between the ends of the flange and a brace rail arranged at an angle other than 90° to the fence post includes a sleeve shaped to receive the end of the rail and a pin attached to the outer end of the sleeve. The pin is adapted to be received in an oversized hole in the post. In some instances the hole may be in the post proper, but in most instances it will be in a square tubular attachment to the post. Each of the flanges has a notch in its end aligned with the notch of the other flange and the tubular attachment has top and bottom outwardly extending lugs on two adjacent sides which extend into the aligned notches with these adjacent sides bearing against the flanges. The oversized holes are provided in each of the other two sides of the tubular member. An angle having a threaded hole therethrough at the junction between its legs is positioned within the post with its legs bearing against the flanges. The tubular member has a hole therein in alignment with this threaded hole and a screw passing through that hole into threaded engagement with the threaded hole holds the angular member against the flanges.

CONNECTION BETWEEN A BRACE RAIL AND A FENCE POST

This invention relates to a connection between a brace rail and a fence post and, more particularly, to such a connection to a fence post of the type shown in Ashworth et al U.S. Patent No. 3,370,836 dated Feb. 27, 1968. Prior to my invention, various expedients were used to connect a brace rail to this type of post. None of these was satisfactory for various reasons, such as being unsightly and/or weak. No problem was involved when the rail was horizontal and perpendicular to a side of the post. However, when the rail was not horizontal and/or was not perpendicular to the side of the post, it was extremely difficult to get a good connection with the post. In such a connection the erectors used their own ingenuity to make the connection, but their solutions were such that the purchaser of the fence objected in many instances.

It is therefore an object of my invention to provide a relatively simple, inexpensive and strong connection between a brace rail and a fence post in which the brace rail may be arranged at any angle to the post.

This and other objects will be more apparent after referring to the following specification and attached drawings, in which:

FIG. 1 is a top plan view showing my connection between a brace rail and a corner post with the other end of the rail being connected to a line post;

FIG. 2 is an elevation of FIG. 1;

FIG. 3 is an enlarged plan view showing details of the connection;

FIG. 4 is an end view of a fitting used in my connection;

FIG. 5 is a side view of the fitting of FIG. 4; and

FIG. 6 is a perspective view of a tubular member forming part of the connection.

Referring more particularly to the drawings, reference numeral 2 indicates an L-shaped corner post having two sides 4 arranged at right angles to one another, a short side 6 connected to the free end of each side 4 and arranged at right angles thereto, and an inwardly extending flange 8 attached to and arranged at right angles to each side 6 with vertically spaced notches 9 being provided in the end of each flange 8 with the notches in one flange aligned with the notches in the other flange. A vertical opening 10 is provided between the ends of flanges 8. According to my invention, I provide a rectangular end cup 12 which has a sleeve or receptacle 14 for receiving a trigonal rail 16 of the type shown in my above mentioned patent. When used with other types of rails, it only being necessary that the receptacle 14 be shaped to conform to the shape of the rail or to the shape of the end of the rail. Attached to the receptacle 14 is a bracket 18 having a cylindrical pin 20 attached thereto with its axis in alignment with the axis of receptacle 14. The top of the bracket 18 is frusto-spherical as shown in FIG. 5 for best operation. In some instances, such as shown in broken lines in FIG. 1, it is only necessary to provide a hole 22 in one of the sides 4 with the size of the hole being somewhat larger than the diameter of the pin 20 so that the axis of the pin can be at an angle to the axis of the hole. Since the rail 16 is always in compression, it is impossible for the pin 20 to slip from the hole 22.

Since the fence fabric 24 is attached to apertures 25 on the sides 6, the brace rails are preferably attached to

the post inside the fabric 24. To accomplish this, I provide a short angle 26 having a threaded hole 28 extending therethrough at the junction between the legs of the angle with the axis of the hole 28 being at an angle of 45° with each of the legs of the angle. I also provide a rectangular, preferably a square, tubular member 30 having top and bottom outwardly extending lugs 32 on two adjacent sides thereof. A hole 34 is provided in each of the other two sides of tubular member 30 intermediate its height. A hole 36 is provided in the corner of the member 30 between the sides having the lugs 32 thereon and a hole 38 is provided in the diagonally opposite corner with the axes of the holes 36 and 38 being in alignment. The height of the member 30 is slightly less than the height of notches 9.

The members 26 and 30 are assembled on the post, as follows: The angle 26 is placed within the post 2 with its legs bearing against the flanges 8. The member 30 is placed against the outside of the post 2 with its lugs 32 being received in two aligned notches 9 in the flanges 8, thus positioning the member 30 at the desired elevation. In this position the holes 36 and 38 as best shown in FIG. 3 will be in axial alignment with the hole 28 in angle 26. A counter-sunk head cap screw 42 passes through hole 36 and is threaded into the hole 28. The head of the screw 42 is preferably provided with an Allen head so that the screw 42 can be easily tightened to hold the members 26 and 30 in secure position against the flanges 8. This is done by inserting an Allen wrench through the opening 38. A rail 16 with an end cup 12 attached thereto can then be inserted into either or both openings 34 as shown in FIG. 3. Due to the size of openings 34, the rail 16 can be arranged at various angles as shown.

In some instances an end cup 12 will be attached to the other end of a brace rail 16 with the length of brace rail 16 being so selected that the pin 20 of the end cup 12 at the lower end of brace rail 16 can be received in an opening 44 in the web of an adjacent line post 46 as shown in FIG. 2.

While one embodiment of my invention has been shown and described, it will be apparent that other adaptations and modifications may be made without departing from the scope of the following claims.

I claim:

1. A connection between a brace rail and an L-shaped fence post, said post having two connected long sides, a short side connected to the free end of each of said long sides and extending in substantially the same direction as the other of said long sides, and an inwardly extending flange attached to each of said short sides; said connection comprising a tubular member having a hole through the wall thereof, means connecting said tubular member to said flanges on the outside thereof, an end cup including a sleeve shaped to receive the end of the rail, and a pin attached to the outer end of said sleeve and adapted to be received in said hole.

2. A connection according to claim 1 in which said two long sides are arranged at right angles to one another, and in which each of said flanges is at right angles to the short side to which it is attached with a vertical opening between the ends of said flanges.

3. A connection between a brace rail and a fence post, said fence post having two long sides arranged at

right angles to one another, a short side connected to the free end of each long side at right angles thereto, and an inwardly extending flange attached to each short side at right angles thereto with a vertical opening between the ends of said flanges, each flange having a notch in its end aligned with the notch of the other flange, said connection comprising a tubular member secured to said post and bearing against the outside of said flanges, said tubular member having a hole therein, an end cup including a sleeve shaped to receive the end of the rail, and a pin attached to the outer end of said sleeve and adapted to be received in said hole.

4. A connection according to claim 3 in which said tubular member is square in horizontal section and includes top and bottom outwardly extending lugs on two adjacent sides extending into said aligned notches, the other two sides of said tubular member each having a pin receiving hole therein of substantially larger cross section than said pin.

5. A connection according to claim 4 including an angle within said post with its legs bearing against said flanges, said angle having a threaded hole therethrough at the junction between its legs, said tubular member having a hole therein in alignment with said threaded

hole, and a screw passing through said last named hole into threaded engagement with said threaded hole to hold the angle and tubular member against said flanges.

6. A connection according to claim 3 in which said end cup includes a generally conical bracket having its base attached to said sleeve, and a frusto-spherical top connected to said pin.

7. A connection according to claim 6 in which said tubular member is square in horizontal section and includes top and bottom outwardly extending lugs on two adjacent sides extending into said aligned notches, the other two sides of said tubular member each having a pin receiving hole therein of substantially larger cross section than said pin.

10 8. A connection according to claim 7 including an angle within said post with its legs bearing against said flanges, said angle having a threaded hole therethrough at the junction between its legs, said tubular member having a hole therein in alignment with said threaded hole, and a screw passing through said last named hole into threaded engagement with said threaded hole to hold the angle and tubular member against said flanges.
